UNITED STATES PATENT OFFICE.

THADDEUS C. COLE, OF HERINGTON, KANSAS.

COMBINATION-MOLD FOR CONCRETE FENCE POSTS AND BRACES.

1,085,593.

Specification of Letters Patent.

Patented Feb. 3, 1914.

Application filed March 20, 1912. Serial No. 684,941.

To all whom it may concern:

Be it known that I, THADDEUS C. COLE, a citizen of the United States, residing at Herington, in the county of Dickinson and State of Kansas, have invented a new and useful Combination-Mold for Concrete Fence Posts and Braces, of which the following is a specification.

My invention relates to combination molds for fence posts and braces, and has for its object a mold of simple, durable and inexpensive construction.

A further object of my invention is to provide a combination mold for fence posts and braces whereby the line posts, corner post and corner braces can be molded simultaneously.

A further object of my invention is to provide a combination mold for fence posts and braces which can be readily assembled and disassembled at the place where used.

A further object of my invention is to provide means for positively preventing the base boards from being moved outwardly.

A further object of my invention is to provide means for positively preventing the end boards from moving longitudinally of the mold after the mold has been assembled.

The above and other features of novelty, advantages, and capabilities of my invention will become apparent from a detailed description of the accompanying drawings, in which—

Figure 1 is a plan view of a mold constructed in accordance with my invention, showing the mold assembled, Fig. 2 is a cross section of the same taken on the line 2—2 of Fig. 1; Fig. 3 is a longitudinal section of the same taken on the line 3—3 of Fig. 1. Fig. 4 is an enlarged detail view of one of the end blocks in the brace mold.

With my mold the line posts, the corner posts and the braces can be molded simultaneously.

A designates the molds for molding the corner posts, B the mold for molding the line posts, and C the mold for molding the braces.

Referring to the accompanying drawings in detail, I have used the reference number 10 to designate the base boards of the molds for making the line posts and braces, and 11 the base board for the molds for making the corner post. I have only shown one mold for making the corner post, and one for molding the braces, but it is understood that one

or more may be used in my mold. The base boards 10 and 11 are provided with strips 12 which form the chamfer on one side of the posts and braces, and also serves to hold the partition boards 13 in place. The outer base board 10 is provided with a strip 14 which engages the side board 15 and prevents the base boards from being displaced outwardly in this direction, and the base board 11 is provided with a strip 16 which engages with the side board 15^a and prevents the base boards from being displaced in the opposite direction. The partition boards 13 are provided with beveled portions 17 which form the chamfers on the upper side of the posts.

The end board 18 rests upon the brace boards 10 and 11 and is provided with grooves to receive the ends of the partition boards and the side boards 15 and 15^a. The ends of the end board 18 are provided with eyes designed to receive hooks 19 which are secured to the side boards 15 and 15^a. On each of the base boards 10 and 11 is rigidly secured a block 20 against which the outside of the side boards 15 and 15^a lie. Thereby lateral movement of the frame is prevented.

The end board 20 is substantially the same as the end board 18 save that it is designed to fit into grooves formed in the base boards 10 for preventing longitudinal displacement of the base boards, and is provided with a hook designed to engage an eye secured to the reinforcing block 22, which block is secured on the exterior of the partition and side member 23, and engages the end of the end board 20 and reinforces it against outward movement. The partition and side member 23 is provided with a beveled portion 29, which forms the chamfer on the upper side of the line post, and with a beveled portion 25 which forms the chamfer on the upper side of the corner post.

The end board 26 rests on the base 11 and is provided with grooves designed to receive the ends of the partition board 23 and the side board 15^a, and hooks for detachably connecting the ends and side.

The brace which is molded in the brace mold C is what is termed a straight brace, that is a brace which extends from the top of the corner post to the top of the line post. For molding the end of the brace which engages the corner post, I provide a block 27 provided with an integral beveled shoulder

27^a (as best shown in Fig. 4.) For forming the opposite end of the brace I provide a block 28. However the form of these blocks may be changed to mold any desired form 5 end, therefore I do not wish to limit myself to the specific form shown. As the corner braces are made in rights and lefts, I accomplish this by turning the block 27 so that its beveled edge will form either a 10 right or left brace as desired.

In setting up my mold the base board 11 is first laid down and then the remaining base boards in the order shown. The end boards and sides are then placed in position 15 and secured together by the hooks. The partition boards are then placed in their position and the mold is then ready for use. After the molds have been filled with concrete and it is desired to again use the mold, 20 the hooks are disengaged and the mold taken apart, the post and brace removed and the mold is then assembled as above stated.

While I have herein shown and described only one embodiment of my invention, it is 25 to be understood that various changes and modifications may be made by those skilled in the art without departing from the scope of my invention as defined by the appended claims.

30 Having thus described my invention, what I claim as new and desire to secure by Letters Patent of the United States is:

1. In a gate mold for fence posts, a frame composed of a base board for brace molds, 35 a plurality of base boards for line post molds, a base board for corner post molds, a side boundary board on each side of the gate mold, partition boards on the contacting line of the respective base boards, an end board at one end of the gate mold forming 40 the boundary line for all of the molds, a second end board at the other end of the gate mold forming the boundary line for all of the molds except the corner post mold, 45 means for detachably connecting said side boundary boards and end boards together, a block on each of the end base boards against which the side boards will contact and secure the gate mold from lateral movement, 50 and a groove extending across all of said base boards except the corner post base

board to receive said second end board thereby to prevent longitudinal movement of said base boards.

2. In a combination mold for line posts, 55 corner posts and braces comprising a plurality of base boards, the base boards for said corner posts being of greater length than the base boards for the line posts, side boards for said corner posts and brace molds, 60 partition boards on the contacting line between the remaining base boards, end boards for said molds, means for detachably securing said parts together, and means for preventing longitudinal movement of the base 65 board for said corner post mold.

3. In a combination mold for line posts, corner posts and braces comprising a plurality of base boards, the base boards for said corner posts being of greater length 70 than the base boards for the line posts, side boards for said corner posts and brace molds, partition boards on the contacting line between the remaining base boards, an end board at one end of said base boards having 75 dove-tailed connection with the side boards and partition boards, a second end board for the opposite end of said molds and having dove-tailed connection with all of said base boards except the base board for the corner 80 post, an end board for said corner post mold, means for detachably securing said parts together, and means secured to one of the side boards of said corner post mold to prevent longitudinal movement of said mold 85 with respect to the remaining molds.

4. In a device of the class described, a brace mold comprising base boards provided with a groove near one end, side boards and partitions, end boards, one of 90 said end boards being designed to engage the groove in said base boards, blocks provided with integral shoulders in either end of said mold and means for detachably securing the parts together.

In witness whereof, I hereunto subscribe my name this fourteenth day of March A. D. 1912.

THADDEUS C. COLE.
